UNITED STATES PATENT OFFICE.

JAMES M. OSGOOD, OF SOMERVILLE, MASSACHUSETTS.

CURTAIN-FIXTURE.

SPECIFICATION forming part of Letters Patent No. 308,038, dated November 11, 1884.

Application filed July 23, 1883. (No model.)

To all whom it may concern:

Be it known that I, JAMES M. OSGOOD, a citizen of the United States, residing at Somerville, in the county of Middlesex and State of Massachusetts, have invented a new and useful Curtain-Fixture, of which the following is a specification.

My invention relates to improvements in spring-curtain fixtures in which the catch operates upon the spindle and locks directly into the cap or ferrule upon the head of the roller. I attain these objects by the mechanism illustrated in the accompanying drawings.

Figure 1 shows the spindle end of the roller with ferrule attached. Fig. 2 is a longitudinal section through the center of the roller. Fig. 3 shows two methods of making notched projections on the spindle. Fig. 4 is the cap end of the ferrule. Fig. 5 shows a perspective view of the spindle and catch. Fig. 6 is a face and top view of catch C, which has a hole through its center sufficiently large to allow a free movement. The tooth or flanged portion c' of catch C is provided at one side with an abrupt shoulder locking into the ferrule, while the opposite shoulder is beveled to permit the tooth to be withdrawn from the slot x of the ferrule when the curtain is being pulled down. The catch sets within the bore of the roller, which makes a chamber to operate in.

Having described my invention, what I claim as new, and desire to secure by Letters Patent, is—

1. In a curtain-roller, the combination of spindle A, having lateral projections p, with a disk-shaped catch, C, provided with a tooth or flanged portion, c', and a central aperture, a, and lateral slots s, loosely mounted on the spindle to have a tilting action, and the ferrule B, with which the pawl or catch C engages, substantially as set forth.

2. In a spring curtain-roller, the combination of spindle A, provided with lateral projections p, with the pawl or catch C, loosely fitted thereon, and the combined ferrule and end cap, B, having locking-aperture x, substantially as shown and described.

3. In a spring curtain-roller, the combination of spindle A, provided with lateral projections p, the pawl or catch C, loosely fitted thereon, and the end cap or ferrule, B, having locking-apertures x, the pawl being located within the bore of the roller and the ferrule, substantially as set forth.

JAMES M. OSGOOD.

In presence of—
D. G. HASKINS, Jr.,
GEO. F. WHITMORE.

ing from the periphery at right angles to its face, having a central aperture, a, therein, and provided with lateral slots s, through which central aperture, a, the spindle passes, 55 said catch being held loosely upon its spindle, as shown in Fig. 5, to obtain a tilting motion, while it is prevented from axial motion by radial projections p upon the spindle, which enter the lateral slots s in said catch. The 60 spindle-end projections and notches are made of one piece of metal.

Fig. 6 is a face and top view of the catch C, which has a hole through its center sufficiently large to allow a free movement. The 65 tooth or flanged portion c' of catch C is provided at one side with an abrupt shoulder locking into the ferrule, while the opposite shoulder is beveled to permit the tooth to be withdrawn from the slot x of the ferrule when 70 the curtain is being pulled down. The catch sets within the bore of the roller, which makes a chamber to operate in.

Having described my invention, what I claim as new, and desire to secure by Letters 75 Patent, is—

1. In a curtain-roller, the combination of spindle A, having lateral projections p, with a disk-shaped catch, C, provided with a tooth or flanged portion, c', and a central aperture, 80 a, and lateral slots s, loosely mounted on the spindle to have a tilting action, and the ferrule B, with which the pawl or catch C engages, substantially as set forth.

2. In a spring curtain-roller, the combination of spindle A, provided with lateral projections p, with the pawl or catch C, loosely fitted thereon, and the end cap or ferrule, B, having locking-apertures x, substantially as shown and described.

3. In a spring curtain-roller, the combination of spindle A, provided with lateral projections p, the pawl or catch C, loosely fitted thereon, and the end cap or ferrule, B, having locking-apertures x, the pawl being located 95 within the bore of the roller and the ferrule, substantially as set forth.
